UNITED STATES PATENT OFFICE.

OTHO M. OTTE, OF TARENTUM, PENNSYLVANIA.

CLOTHES WRINGER.

Application filed January 18, 1923. Serial No. 613,395.

To all whom it may concern:

Be it known that I, OTHO M. OTTE, a citizen of the United States, and a resident of Tarentum, in the county of Allegheny and

5 State of Pennsylvania, have made a new and useful Invention in Clothes Wringers, of which the following is a specification.

This invention relates to clothes wringers and an object thereof is to produce an improved clothes wringer in which the liability to crush buttons or tear the same from clothes is reduced to a minimum.

This, as well as other objects which will readily appear to those skilled in this particular art, I attain by means of the device described in the specification and illustrated in the drawings accompanying and forming part of this application.

In the drawings, Figures 1 and 2 are views in side sectional elevation taken through the center of a wringer embodying this invention. In Fig. 1, the compression rolls of the wringer are shown in operative position and the endless conveyor belt 25 is shown under tension. In Fig. 2, the compression rolls have been slacked and the tension on the conveyor belt has been reduced.

The wringer comprises end posts 3, only 30 one of which is shown and within suitable bearings slidable within slots 4 in the end posts compression rolls 5 and 6 are mounted and geared together in the usual manner (the gearing not being shown in the drawings). Compression roll 5 is preferably 35 formed from cast iron and trued to present a relatively smooth surface. Compression roll 6 is larger in diameter than roll 5 and having a core formed of any suitable material, is covered with a relatively thick, soft 40 rubber covering.

An endless conveyor belt 7 preferably 45 formed of soft rubber, surrounds compression roll 5 and idler rollers 8 and 9 mounted for rotation in support arms 10—10. The conveyor belt which passes between the compression rolls co-operating with soft rubber roll 6 affords the required elasticity for wringing.

50 The roll compression is obtained by means of a spring 11 carried by a follower bar 12 and adjustment screws 13—13, only one of which is shown. Each adjustment screw, by means of two collars 14 and 15 carries 55 a support head 16 which at its center is drilled to loosely receive the adjustment

screw. The depending sides 16^a of the support head are provided with two horizontally extending slots 17—17 and within each of these, a horizontal pin 18 is held by 60 means of cotter pins 19. The upper end of each roller support arm 10 is provided with a vertically elongated slot 20 and pin 18 lies within this slot.

Adjustment screw 13 is provided with a 65 handle 21 and support arms 10 are channeled as shown at 22 to receive a dowel pin 23 secured to the end posts. The side faces of the end posts against which support arms 10 are held by means of conveyor belt 7 70 are generally inclined as shown in the drawings and provided with corrugations adapted to cooperate with reverse corrugations formed on the adjacent faces of the support arms. These corrugations tend to hold the 75 support arms in adjusted position.

As shown in Fig. 1, the compression rolls are in operative position and endless conveyor belt 7 is under tension. In this position, pins 18 are in contact with the tops of 80 the vertically elongated slots in the support arms. The roll compression may be varied by means of adjustment screw 13 without varying the conveyor belt tension, since the 85 corrugations hold the support arms in adjusted position. When it is desired to reduce the tension on the conveyor belt, adjustment screw 13 will be turned up so as to release the spring tension on the rolls and when the screws are backed sufficiently far, 90 the support arms 10 will be lifted by the support head 16 through the agency of pins 18 thereby decreasing the distance between support rollers 8 and 9, thus reducing the 95 tension on the conveyor belt. The horizontal slots 7 of the support head 16 allow the support arms 10 to move laterally of the wringer, while moving vertically thereof. The slots 22 and dowel pins 23 maintain alignment between the support arms and the 100 wringer end posts.

Having thus described my invention, what I claim is:

1. In combination with the compression rolls of a wringer, idler rollers located on 105 opposite sides of the lower roll, an endless elastic belt passing around said idler rollers and the lower compression roll, tension means for varying the roll compression, and supports having a lost motion connection 110 with said means and within which said idler rollers are mounted.

2. In combination with the compression rolls of a wringer, idler rollers located on opposite sides of the lower roll, an endless elastic belt passing around said idler rollers and the lower compression roll, screw-operated spring tension means for varying the roll compression, and supports having a lost

motion connection with said means within which said idler roller are mounted.

In testimony whereof, I have hereunto ¹⁰ subscribed my name this 9th day of January, 1923.

OTHO M. OTTE.
